UNITED STATES PATENT OFFICE.

ADAM LOEB, OF PORTLAND, OREGON.

PIANO-TRUCK.

SPECIFICATION forming part of Letters Patent No. 734,076, dated July 21, 1903.

Application filed December 30, 1901. Serial No. 87,811. (No model.)

To all whom it may concern:

Be it known that I, ADAM LOEB, a citizen of the United States, and a resident of Portland, in the county of Multnomah and State of Oregon, have invented a new and useful Improvement in Piano-Trucks, of which the following is a specification, reference being had to the accompanying drawings as a part thereof.

10 My invention relates to what is known as a "piano-truck," being a contrivance for moving pianos and like objects into and out of dwelling-houses; and it has for its object certain improvements and features which will 15 be hereinafter more fully described and claimed and are designed to render such contrivance more practical and more convenient to use for the purpose intended.

In the drawings, Figure 1 is a side elevation of my improved truck. Fig. 2 is an elevation of the front end of the same. Fig. 3 is a vertical section of the case or housing *h* for the dogs *i i'*. Fig. 4 is a perspective elevation of one of such dogs. Fig. 5 is a section on the line *x x* of Fig. 2. Fig. 6 is an elevation of the disk *n*, said Figs. 2, 3, 4, 5, and 6 showing the means provided for adjustably holding the standard *p'*. Fig. 7 is a plan section of the rear portion of the truck; Fig. 8, a longitudinal section of the rear portion of my truck on a line *x' x'* of Fig. 7, the rod 6 and its coöperating device, however, being shown in end view. Fig. 9 is a detail of the rod 6 and its coöperative devices, said Figs. 35 7, 8, and 9 showing the means provided for adjustably holding the standard *p'*; and Fig. 10 is a cross-section on the line *x'' x''* of Fig. 2.

The letters and numerals designate the parts referred to.

40 The body of my truck is made of boards *a b*, between which are secured blocks *c c' c'' c''*, so as to provide the space for the devices adjustably holding the rear standard *p*, and in the front end of the truck is secured an upright board *d*, to which are secured the devices for adjustably holding the forward standard *p'*. The forward standard consists of a rod *p'*, the middle portion of which is inserted in the cavity therefor provided in the block *c''*. On the extremities of such rod are provided eyes in which to receive the ends

of the axle *p''* of the wheels *p*. The wheels are held in place by means of spring-keys.

In the case *h* are pivoted the dogs *i i'*. Such case consists of a base-plate having 55 screw-holes *h²* and projecting wall portions *h³*, on which to secure the cover *h'*. The head ends of such dogs are adapted to engage the notches *j'* of the bar *j*, such bars sliding vertically through the case *h*. The 60 heads of said dogs are also provided with stud-pins *i²*, which project through the slots 10 10^a of the disk *n*, rotatably secured on the exterior of the cover *h'*.

65 *l* is a bar having projecting portions at its extremities (see Fig. 5) which provide a stop for the cross-bar *j* in the head end of the bar *j* and limit the extreme downward motion of such bar. The bar *l* is secured in place by means of bolts *l' l''*, and on the bolt 70 *l''* is also secured a lever *m*, the left extremity of which has a slotted portion *m'*, in which to receive that portion of the stud-pin *n²* projecting from the exterior of the rotatable disk *n*. The disk *n* controls the positions of the 75 dogs *i i'*—that is to say, keeping them in engagement with the notches of the bar *j* or spreading the free ends of the dogs apart, so as to allow the bar *j* to be moved up and down. In its normal position, in which it is 80 held by the spring *o*, the disk holds the heads of the dogs in engagement with the bar *j*. By lifting the free end of the lever *m* the disk *n* is rotated in the direction of the arrow seen in Fig. 6 against the tension of the 85 spring *o*, with the effect of spreading the dogs *i i'* apart, so as to be able to move the bar *j*, as mentioned, and as soon as the lever *m* is released again the disk *n*, by the action 90 of the spring *o*, will be returned to its normal position and the dogs be ready to engage oppositely-disposed notches of the bar *j*.

The bottom end of the bar *j* is formed into an eye *j''*, in which to receive the stirrup *s*, having eyes at its extremities through which 95 is inserted the axle *p''*.

The straps *g g'* strengthen the forward end of the truck and furnish an additional support for the headboard *d*. Such straps are respectively provided with ears *g²*, in which 100 is inserted a handle-bar *r*. By taking hold of the handle-bar and operating the lever *m*

to release the bar j the standard p' may be adjusted to any desired position. The head end of the board d is provided with a cross-piece e for strength and also with a pair of rollers f or casters f . When the truck is to be stood on an end, the standards p are adjusted forward, and the head end of the truck will then rest on the wheels p^3 and casters f .

11 represents a pair of angular braces for 10 the board d .

k is an auxiliary handle for lifting the front end of the truck.

The rear standard p in construction represents the forward standard p' , and it holds in 15 its extremities the axle p^1 of the wheels p^2 . The middle portion of the standard p is inserted in a movable block q' . (See Fig. 7.) The longitudinal adjustment of the block q' is accomplished by the rod u , one end of 20 which is threaded and inserted in the plate y , having a threaded perforation, and such plate is secured in a cavity therefor provided in the block q' by means of bolts z . The fixed block c is provided with a plate v , which is 25 let into the end of the block and secured in place by means of bolts w . The rod u is provided with a fixed collar u^2 , and to save wear of the block 3 the rod u is also provided with a washer u^3 . The extremity u' of the rod u 30 is squared, so as to receive a key. By manipulating the rod u the block q' can be moved longitudinally to effect the adjustment of the standard p to the requirements and conditions of any particular stairway or hall of a 35 dwelling-house or otherwise. The extremities of the standard p are further adjusted and held in place by means of a pair of arms q , the upper ends of which arms have eyes inserted on the ends of the rod 6 , and the 40 lower ends of the arms have eyes inserted on the axle p^4 within the extremities of the standard p . The rod 6 is provided with a pair of cams 8 8^a and an arm 5 , rotatably inserted on the rod 6 , and to such arm is secured the 45 middle portion of a coil-spring 7 , the ends of which spring engage the extremities of said cams 8 8^a . The sides of the truck-body are provided with rack-bars 9 , and the rod 6 is normally held in place by the action of the 50 spring-controlled cams in a pair of oppositely-disposed recesses of such rack-bars. The extremities 6^a of the rod 6 are squared, so as to receive a key by which to turn the rod 6 against the spring 7 and rotate the cams, so as to clear 55 the rod 6 from its engagement with the rack-bars 9 and allow such bar 6 and therewith the arms q q' to be adjusted to any desired place required for the proper positioning of the standard p . When the truck is resting 60 on what are called "dead" wheels—that is to say, so that neither the forward nor the rear wheels touch the floor—in that case the bar j is lifted, so as to bring the wheels p^3 over in front, and the standard p of the rear wheels 65 is thrown back under the projecting rear portion of the board a , and the standard p is then held in place by means of the hook-head

2 of the bolt 15 , controlled by a coil-spring 3 , catching the axle of the rear wheels. It will be seen that the bolt 15 is longitudinally adjusted with the adjustment of the block q' .

t is a sleeve inserted between the extremities of the arms q on the axle of the wheels p^2 .

To hold the lower end of the bar j against the thrust of the stirrups, the face of the upright board d has a vertical groove 14 and two plates 12 12^a , furnishing guides for a headed stud-pin 13 , projecting from the rear side of the bar j , this feature being clearly illustrated in Fig. 10.

Having fully described my invention, now what I claim, and desire to secure by Letters Patent, is—

1. In a piano-truck comprising a body and pivoted wheel-standards, the mechanism holding the front wheel-standard in adjustable position and comprising, in combination, a slidably-secured bar j , having notches j' ; pivoted dogs i i' , the heads of which are adapted to enter the notches j' ; stud-pins i^2 , on the heads of such dogs; pivoted disk n , having slots 10 , 10^a in which the stud-pins i^2 are inserted; a spring controlling the disk n ; means for rotating the disk, to spread the free ends of the dogs, i i' , apart and thereby release the bar j ; and means limiting the drop of the bar j , when released, substantially as described.

2. In a piano-truck, in combination with a body consisting of boards a , b , and intermediate blocks, a movable block q' ; pivoted standard p ; wheel-axle p^4 , journaled in the extremities of said standard p ; a bail or arm q , on said axle, provided with eyes in its extremities; rack-bars 9 , on the two sides of the rear portion of the truck-body, a rod 6 inserted in the eyes of the bail q , means movably holding said rod 6 in the notches of the bars 9 in which it is inserted, means for longitudinally moving the block q' , and means for securing the axle p^4 , when thrown rearwardly, substantially as described.

3. In a piano-truck, in combination with a body consisting of boards a , b , and intermediate blocks, a movable block q' ; pivoted standard p ; wheel-axle p^4 , journaled in the extremities of said standard p ; a bail or arm q , on said axle, provided with eyes in its extremities; rack-bars 9 , on the two sides of the rear portion of the truck-body, a rod 6 inserted in the eyes of the bail q , fixed cams 8 , 8^a , and a movable arm 5 on the rod 6 , a coil-spring 7 , operating to hold the rod 6 in the notches of the bars 9 , in which it has been inserted, the ends of the rod 6 , being adapted to receive a key for the purpose of moving the rod from one set of notches to another, and means for longitudinally moving the block q' , comprising a rod, or screw-bolt u , a bearing therefor in the fixed block c , and a plate y , secured in the block q' , in which the threaded end of the bolt u , is inserted, substantially as described.

4. A piano-truck consisting of a body made of boards a , b , and intermediate blocks, up-

right d ; casters on the head end of said upright, standard p' pivoted in the fixed block c^2 ; axle, p^5 , journaled in the extremities of said standard p' , wheels on the ends of such axle; bail s , on the axle p^5 ; slidably-secured bar j , having notches j' , which bar is connected to the bail s ; mechanism holding the bar j , in its adjusted position, and comprising pivoted dogs i, i' , the heads of which are adapted to enter the notches j' , stud-pins i^2 , on such heads; disk n , having slots $10 10^a$, in which the stud-pins i^2 of the dogs i, i' , are inserted; a spring controlling said disk, means for rotating the disk, to spread the free ends of the dogs i, i' apart, and thereby release the bar j , and means limiting the drop of the bar when released; the movable block q' ; pivoted standard p ; axle p^4 , journaled in the extremities of said standard p' , wheels on the ends of such axle; a bail or arm, q , on the axle p^4 , provided with eyes in its extremities; rack-bars 9 , on the two sides of the rear portion of the truck-body, a rod 6 inserted in the eyes of the bail q ; fixed cams $8, 8^a$, and a movable arm 5 on the rod 6 ; a coil-spring 7 , operating to hold the rod 6 , in the notches of the bars 9 , in which it has been inserted, the ends of the rod 6 , being adapted to receive a key, for the purpose of moving the rod from one set of notches to another; means for longitudinally moving the block q' , comprising a rod or screw-bolt, u , a bearing therefor in the fixed block c , and a plate y , secured in the movable block q' having a threaded perforation in which is inserted the end of the screw-bolt u ; and the spring-controlled bolt 15 , having a hook-head 2 , for holding the axle p^4 in lifted position, substantially as described.

5. A piano-truck consisting of a body made of boards a, b , and intermediate blocks; upright d ; casters on the head end of said upright; standard p' pivoted in the fixed block c^2 ; axle, p^5 , journaled in the extremities of said standard p' , wheels on the ends of such axle; bail s , on the axle p^5 ; slidably-secured bar j , having notches j' , which bar is connected to the bail s ; mechanism holding the

bar j , in its adjusted position, and comprising pivoted dogs i, i' , the heads of which are adapted to enter the notches j' , stud-pins i^2 , on such heads; disk n , having slots $10 10^a$, in which the stud-pins i^2 of the dogs i, i' , are inserted; a spring controlling said disk, means for rotating the disk, to spread the free ends of the dogs i, i' , apart, and thereby release the bar j , and means limiting the drop of the bar when released; the movable block q' ; pivoted standard p ; axle p^4 , journaled in the extremities of said standard p' , wheels on the ends of such axle; a bail or arm, q , on the axle p^4 , provided with eyes in its extremities; rack-bars 9 , on the two sides of the rear portion of the truck-body, a rod 6 inserted in the eyes of the bail q ; fixed cams $8, 8^a$, and a movable arm 5 on the rod 6 ; a coil-spring 7 , operating to hold the rod 6 , in the notches of the bars 9 , in which it has been inserted, the ends of the rod 6 , being adapted to receive a key, for the purpose of moving the rod from one set of notches to another; means for longitudinally moving the block q' , comprising a rod or screw-bolt, u , a bearing therefor in the fixed block c , and a plate y , secured in the movable block q' having a threaded perforation in which is inserted the end of the screw-bolt u ; and the spring-controlled bolt 15 , having a hook-head 2 , for holding the axle p^4 , in lifted position, substantially as described.

In testimony whereof I have hereunto affixed my signature, in the presence of two witnesses, this 18th day of December, 1901.

ADAM LOEB.
